[57] CLAIM

The ornamental design for a display rack for wine bottles, substantially as shown and described.

DESCRIPTION

FIG. 1 is a front elevational view of a display rack for wine bottles showing my new design;
FIG. 2 is a rear elevational view thereof;
FIG. 3 is a side elevational view taken from the left of FIG. 1;
FIG. 4 is a top plan view thereof; and,
FIG. 5 is a bottom plan view thereof, on a reduced scale.
